DESIGN FOR A MOVABLE BAR

Jacob Zatzkin, Brooklyn, N. Y.

Application December 23, 1933. Serial No. 50,205

Term of patent 3½ years

To all whom it may concern:

Be it known that I, JACOB ZATZKIN, a citizen of the United States, residing at Brooklyn, in the county of Kings and State of New York, have invented a new, original, and ornamental Design for Movable Bars, of which the following is a specification, reference being had to the accompanying drawing, forming a part thereof.

Fig. 1 is a front perspective view of a movable bar showing my new design.

Fig. 2 is a rear perspective view of the same.
Fig. 3 is a plan view of the same.

I claim:

The ornamental design for a movable bar as shown.

In testimony whereof I have affixed my signature.

JACOB ZATZKIN.
